UNITED STATES PATENT OFFICE.

HUBERT SPINDELER, OF NEW YORK, N. Y.

RAIL-BED.

SPECIFICATION forming part of Letters Patent No. 237,332, dated February 1, 1881.

Application filed October 31, 1878.

To all whom it may concern:

Be it known that I, HUBERT SPINDELER, of the city, county, and State of New York, have invented a new and useful Improvement in 5 Rail-Beds, which improvement is fully set forth in the following specification, reference being had to the accompanying drawings, in which—

Figure 1 represents a cross-section of a rail-bed embracing my invention. Fig. 2 is a similar section thereof, taken in a different plane than in Fig. 1. Fig. 3 is a plan or top view thereof.

Similar letters indicate corresponding parts. 15 My invention relates to beds or supports for railroad-rails, and especially those of elevated railroads, its object being to abate or prevent the vibration of the parts of the structure by the action of the rails and to obviate the noise 20 due to this cause.

My invention consists in the combination of a trough containing sand or other incompact substance, a stringer which is secured in said trough and provided with side flanges to cover 25 the joint between them, and a railroad-rail fastened to the stringer, all of which will be fully hereinafter described in detail.

In the drawings, the letter A designates a railroad-rail fastened to a stringer, B, in the 30 usual way, and C is a trough partially filled with sand or other like substance, in which the stringer is secured according to my invention. The trough C is made of equal length to the stringer and rail—that is to say, the same extends the entire length of the road on which 35 my invention is used, and for the purpose of securing the stringer within the trough I make use of bolts *a b*; but other well-known devices can obviously be substituted therefor.

40 In order to isolate and produce a tight joint between the stringer B and the trough C, I

combine therewith packing-strips D, of india-rubber or other material, and a layer, *c*, of asphaltum or other similar material.

A sufficient quantity of sand or other incompact substance is placed in the trough C to cause the stringer B to rest thereon, and by reason of its peculiar nature a very effective isolation of the rail from the structure of the road is thereby produced.

The stringer B is provided with laterally-projecting flanges *d d* on its upper edges, which, in the example shown, are made separate therefrom and joined thereto by means of a mortise and tenon. These flanges *d d* serve 50 to cover the joint between the stringer B and the trough C, and thus effectually prevent the admission of rain-water to the trough.

On the upper edges of the trough C are formed or secured eaves or gutters E, which 55 serve to catch the rain-water dropping on and running off the stringer B. These eaves E may be arranged to discharge at suitable points through pipes *e*, and when my invention is applied to an elevated railroad they serve to 60 prevent the rain-water falling on the stringers from dripping down on the street.

What I claim as new, and desire to secure by Letters Patent, is—

The combination of a trough containing sand 70 or other incompact substance, a stringer which is secured in said trough and provided with side flanges to cover the joint between them, and a railroad-rail fastened to the stringer, substantially as described.

In testimony that I claim the foregoing I hereunto set my hand and seal this 26th day of October, 1878.

HUBERT SPINDELER. [L.S.]
